UNITED STATES PATENT OFFICE.

DORA DUNCAN, OF NEW YORK, N. Y.

CARPET-SWEEPER SHIELD.

1,250,817.

Specification of Letters Patent. Patented Dec. 18, 1917.

Application filed April 1, 1916. Serial No. 88,267.

To all whom it may concern:

Be it known that I, DORA DUNCAN, a citizen of the United States, and a resident of New York, in the county of New York and State of New York, have invented certain new and useful Improvements in Carpet-Sweeper Shields, of which the following is a specification.

My invention relates to that type of carpet sweepers which employ rotary brushes, suitably housed, operated by rollers rolling over the carpet, and the main object of the invention is to provide a readily attached shield for a sweeper which will fully protect articles of furniture from injury due to the contact of the sweeper therewith.

These sweepers as at present marketed are provided with a guard around the edge and with resilient corner bumpers, but no guard is provided for the pivoted handle yoke, nor for the handle, as when forcing the sweeper beneath chairs, beds, and other articles of furniture of the "sanitary" type, and injury results to such furniture, especially when the sweeping is being done by more or less careless servants, and it was in order to prevent this that my invention was conceived.

My invention is fully described in the following specification, of which the accompanying drawings form a part, in which like characters refer to like parts in each of the views, and in which:—

Figure 1 is a perspective view of a carpet sweeper provided with my shield, ready for use;

Fig. 2 is an enlarged section taken on the line 2—2 of Fig. 1;

Fig. 3 is an enlarged fragmentary section taken on the line 3—3 of Fig. 1; and

Fig. 4 is an enlarged section taken on the line 4—4 of Fig. 1.

My shield is provided as a separate article of manufacture, and is preferably formed in one piece, as a unit, whereby no parts may be lost or mislaid previous to the installation thereof upon a sweeper, but I do not limit myself to this unitary construction as the same protective results would occur if the shield was made of separable members.

Referring to the drawings 5 represents the housing of a conventional carpet sweeper having the usual rollers 6, cylindrical brushes 7, pivotally mounted yoke 8, and

handle 9, a protecting bead 10 being indicated in Fig. 2 of the type now vended as a part of the sweeper.

My shield comprises a body portion 11 entirely covering the top surface of the housing 5, a band 12 for the edges of said housing, a pocket 13 for the yoke 8, a cylindrical member 14 for the handle, and connecting members 15 between the band 12 and the respective ends of the pocket 13.

In order to assemble the shield upon a sweeper it is necessary to pass a portion thereof, the body portion 11, beneath the yoke 8, and I have therefore formed the band 12 of two members 12^a and 12^b each encircling one-half of the edges of the sweeper and having their ends joined at 12^c, as by snap fasteners of the glove type.

The band 12 presents two soft resilient beads 12^d and 12^e to the legs of furniture, and the connecting members 15 are also preferably made in the form of soft beads and are extended along the side and top edges of the yoke pocket 13 to prevent injury by the yoke 8, and I also preferably provide longitudinally arranged beads 14^a and 14^b on the handle covering member 14 to prevent injury by the handle, this member 14 being of a length lending protection for the distance that a sweeper is likely to be forced beneath an article of furniture, a bead 14^c being also provided at its top.

In installing the shield the band fasteners 12^c are disengaged, the handle 9 inserted into the cylindrical member 14 from the bottom thereof and the shield is moved downwardly until the open bottom pocket 13 receives the yoke 8, after which the body member 11 is arranged in position beneath the yoke 8, and the band members joined at 12^c, the shield then being ready for use.

It will thus be seen that I provide an article of manufacture and sale adapted for use upon a carpet sweeper for the protection of furniture and not requiring any change in the structure of the sweeper, and I may, as shown in Fig. 1, slit the body member 11 for the dust pan trip levers 16.

The shield will be composed of relatively soft material, such as fabric, carpeting, leather, imitation leather, or the like and, while I have shown a thoroughly practical embodiment of the invention as to its method of connection with a sweeper, it will be obvious that changes thereover may be made.

providing such changes come within the scope of the appended claims.

Having fully described my invention, what I claim as new, and desire to secure by Letters Patent, is:—

1. An article of the class described, comprising a covering member arranged to cover the body of a carpet sweeper when in use, a band arranged at the lower part of the covering member, and spaced cushioning beads arranged on each side of said band.
2. An article of the class described, comprising a body adapted to cover a carpet sweeper when in use, a band arranged at the lower part of said body, a pocket member covering the yoke of said sweeper, a bead positioned on the edge of said pocket member connected to said band, a handle covering member extending from said pocket member, and a bead extending along

said handle covering member longitudinally thereof.

3. An article of the class described, comprising a body formed to inclose the body of a carpet sweeper when in use, protecting members arranged adjacent the lower edge of said body, a bead extending from said protecting members along the yoke of the carpet sweeper, and a tubular member extending from said bead provided with beads arranged on the handle of said carpet sweeper.

4. As an article of manufacture, for use on a carpet sweeper, a shield comprising a body member, a band formed of two sections, fasteners for the respective ends of said band sections, a yoke pocket having an open bottom, members connecting said band and yoke pocket, and a cylindrical handle receiving member.

DORA DUNCAN.
